UNITED STATES PATENT OFFICE

2,016,982

MAGNETOELECTRIC MACHINE

William Bradford, Hampstead, London, England,
assignor to Wico Electric Company, West
Springfield, Mass., a corporation of Massachu-
sets

Application October 6, 1934, Serial No. 747,216
In Great Britain February 1, 1933

4 Claims. (Cl. 123—149)

This invention relates to magneto-electric machines commonly called magnetos, such as may be conveniently employed in the ignition systems of internal combustion engines, and is especially useful in connection with motorcycles.

It is an object of the invention to provide a magneto-electric machine having an improved and simplified drive connection from the crank or other shaft of the internal combustion engine, and wherein the customary independent operating cam for the interrupter or circuit breaker mechanism is eliminated.

It is a further object of the invention to provide a magneto-electric machine having improved and simplified means for advancing or retarding the spark.

In a magneto-electric machine for internal combustion engines, comprising a rotor member and interrupter or circuit breaker mechanism actuated according to the invention, the crank-shaft, camshaft or other shaft of the engine, provides means for positively driving the rotor member of the magneto, and constitutes the sole means for operating the interrupter or circuit breaker mechanism.

The invention consists in providing a driving shaft profiled to afford cam lobes or surfaces which are appropriate for the timed actuation of the interrupter or circuit breaker mechanism and adapted to effect a keying or like drive coupling with the rotor.

The present invention also consists in a magneto-electric machine for internal combustion engines, comprising a rotor member mounted upon an integral extension of the engine crank-shaft, camshaft, or other shaft, and interrupter or circuit breaker mechanism operated by a cam member formed in said integral extension.

The interrupter or circuit breaker mechanism is mounted upon a base or stator member, which is adjustable relatively with respect to the engine shaft to advance or retard the timing as and when required.

Reference will now be made to the accompanying drawings, in which:

Figure 1 is a front view of a magneto-electric machine for a motorcycle, by way of example, to which the present invention is applied. The machine is shown with its cover removed, and looking on the end of the engine shaft.

Figure 2 is a perspective view of an end of a shaft illustrating one form of profiling according to the present invention.

Figure 3 is a perspective view of a convenient

form of rotor member adapted for use with the shaft according to Figure 2.

Figure 4 is a rear view of the magneto-electric machine according to Figure 1 when removed from the engine shaft.

Figure 5 is a fragmentary view of a motorcycle engine embodying the equipment shown in Figures 1 to 4.

The invention is shown carried into effect according to one convenient mode, as applied by way of example, to a magneto-electric machine 10 for a motorcycle, the machine being mounted upon the crank case 34 and adapted to be driven by the engine crankshaft 11.

The machine 10 may be of any suitable form, and, in the example given, has a rotor 12 adapted to be rotated within a stator member indicated generally at 13, and is provided with customary interrupter or circuit breaker mechanism 14.

In order that the engine shaft 11 may serve as the drive shaft for the magneto 10, it is provided with, or modified to provide, a special flat surface 15 adjacent one end, as hereinafter described, such as to afford a modified or substantially D-shaped cross-section to the shaft 11 in the appropriate locality.

The rotor member 12 may comprise straight or bar permanent magnets 16, with or without end laminations 17 disposed about a tube or sleeve (not shown) of non-magnetic material and maintained in position by end plates 18, 19 of non-magnetic material.

The rotor member 12 has affixed thereto a plate or plates 20, preferably of hardened steel, having a D-shaped hole or holes 21 therein corresponding to the D-shaped cross-section of the shaft 11 afforded by the flat surface 15.

The rotor 12 is thus provided with a positive drive of simple yet efficient construction. To assemble the rotor 12 in its operating position it is merely slipped over the end of the engine shaft 11, which is provided with the surface 15, and it is located in position by means of a spring clip 22 having a projection or the like 23, or with a spring urged detent or the like, which engages a depression 24 suitably located on the engine shaft 11.

The shaping or profiling of the D-shaped portion of the shaft 11 is designed and effected further to provide a cam lobe 25 for operating the interrupter or circuit breaker mechanism 14.

In a particular instance, referred to by way of example only, the flat or cam surface 25 was provided at an angle of 57° in advance of dead

centre position to furnish a spark 15° in advance of dead centre position.

The machine may be mounted upon the crank case or the engine casting in any desired manner. For example, it may be fixed directly onto the crank case 34.

According to a preferred method, the base plate 26 of the machine 10 is provided with a bore 27 having a bearing fit on a boss 28 of the engine 10 (see Figure 5) and with lateral extensions or lugs 29, 30 having arcuate slots 31, 32 therein. The machine may then be bolted down by means of studs or bolts 33 to the crank case 34, or the engine casting as the case may be, the slots 31, 32 providing facility for initially adjusting the setting.

In a preferred arrangement an adjustment of plus or minus 12½° is provided, but any other desired working limits may be obtained.

20 As shown in Figure 5 a flywheel 35 is affixed to the shaft 16 on the opposite end from that at which the machine 10 is located.

Having now described my invention what I claim as new and desire to secure by Letters Patent is:—

1. A magneto-electric machine for internal combustion engines comprising a drive shaft, a stator member provided with a bore or aperture having a bearing fit upon a boss on the engine and being adjustable rotatively with respect to said drive shaft to advance or retard the timing, a rotor member mounted upon an integral extension of said drive shaft, spring urged means for retaining the rotor member in operative position upon said shaft, and interrupter mechanism operated by a cam member formed in said integral extension.

2. A magneto-electric machine for internal combustion engines comprising a drive shaft, a stator member provided with a bore or aperture

having a bearing fit upon a boss on the engine and being adjustable rotatively with respect to said drive shaft to advance or retard the timing, laterally extending lugs on said stator member having arcuate slots therein whereby the machine may be secured by bolts to the engine in adjusted position, a rotor member and interrupter mechanism, said drive shaft having cam surfaces which are appropriate for the timed actuation of said interrupter mechanism and effecting a drive coupling with said rotor.

3. A magneto-electric machine for internal combustion engines comprising a drive shaft, a stator member provided with a bore or aperture having a bearing fit upon a boss on the engine and being adjustable rotatively with respect to said drive shaft to advance or retard the timing, laterally extending lugs on said stator member having arcuate slots therein whereby the machine may be secured by bolts to the engine in adjusted position, a rotor member mounted upon an integral extension of said drive shaft, and interrupter mechanism operated by a cam member formed in said integral extension.

4. A magneto-electric machine for internal combustion engines comprising a drive shaft, a stator member provided with a bore or aperture having a bearing fit upon a boss on the engine and being adjustable rotatively with respect to said drive shaft to advance or retard the timing, laterally extending lugs on said stator member having arcuate slots therein whereby the machine may be secured by bolts to the engine in adjusted position, a rotor member mounted upon an integral extension of said drive shaft, spring urged means for retaining the rotor member in operative position upon said shaft, and interrupter mechanism operated by a cam member formed in said integral extension.

WILLIAM BRADFORD. 40
